CLEANING APPARATUS WITH LUBRICATOR
THEREFOR

Joseph D. Rule, Kewanee, Ill., assignor to Kewanee Industrial Washer Corp., Kewanee, Ill., a corporation of Illinois

Application October 24, 1945, Serial No. 624,203

6 Claims. (Cl. 134—89)

1

This invention relates to cleaning apparatus and more particularly to the type employing a tank to contain benzine, alcohol or the like for cleaning machine parts, small tools, and similar articles.

One object of the invention is to provide a new and improved cleaning apparatus with means for re-circulating the cleaning fluid through the tank and for creating turbulence in the body of the fluid to assist in the removal of grease and dirt from the parts under treatment.

Another object of the invention is to provide a new and improved cleaning apparatus which includes a tank for a cleaning fluid and a reticulated support within the tank at a distance above the bottom thereof so as to provide a settling space below the support for solid matter loosened and removed from the articles under treatment by the action of the cleaning fluid.

It is also an object of the invention to provide an improved cleaning apparatus having a tank in which cleaning fluid is re-circulated and a reticulated support in the tank for articles to be cleaned, said support being readily removable from the tank either with or without such articles.

A further object of the invention is to provide an improved cleaning apparatus including a tank for cleaning fluid, and re-circulating means comprising a housing outside the tank with an inlet to the housing from the tank below the liquid level therein and an outlet discharging into the tank above the normal liquid level, together with a rotary impeller for circulating the liquid through the housing from the inlet to the outlet. The invention also includes a horizontally elongated discharge nozzle leading from the housing and directing the cleaning fluid obliquely into the body of fluid in the tank and across a substantial portion of the width of the tank for agitating the fluid therein and facilitating the cleaning action.

It is an additional object of the invention to provide a cleaning apparatus including a tank for cleaning fluid and a rotary impeller for re-circulating the fluid and to provide bearing means for the drive shaft of the impeller adapted to be substantially leak-proof with respect to the cleaning fluid.

Other objects and advantages of the invention will appear from the following description taken in connection with the drawings, in which:

Fig. 1 is a vertical sectional view of a cleaning apparatus embodying this invention;

Fig. 2 is a detail section taken substantially as

2

indicated at line 2—2 on Fig. 1 to show the proportions of the discharge nozzle;

Fig. 3 is a vertical axial section taken through the bearing sleeve for the impeller shaft and showing a fragment of the adjacent wall of the housing;

Fig. 4 is an elevation partly in section showing a modification of the invention designed for use as a dish washer;

Fig. 5 is an elevation partly in section showing another modification designed for use as a foot-treating bath.

In the form shown in the drawings to illustrate the invention, the apparatus includes a tank 10 having a bottom wall 11 supported at a convenient height on legs 12. It is preferably rendered portable by means of caster wheels 14 so that it can be moved about readily in a garage or machine shop in which it is used. The tank normally contains cleaning fluid such as benzine or other material adapted for cleansing the particular parts or materials to be treated, and the normal level of the fluid in the tank will be maintained approximately as indicated at 16. A grill or reticulated support 18 is disposed in the tank at a considerable distance below the level 16 and at some distance above the bottom of the tank so that a space 20 is provided which serves as a settling chamber to receive solid matter loosened from the articles under treatment.

Intermediate the plane of the support 18 and the liquid level 16, the tank is formed with an opening 22 which serves as the inlet to a housing 24 disposed outside the tank and forming a passageway which leads to an outlet or discharge nozzle 26 at a point in the wall of the tank above the liquid level 16. At the inlet and adjacent thereto the cross section of the housing 24 is substantially circular, as indicated in Fig. 2, and there is rotatably mounted therein an impeller 28 carried by a drive shaft 30 which is journaled in a bearing sleeve 32 extending outside the housing 24. At its outer end the shaft 30 carries a pulley 34 connected by a belt 36 to the drive pulley 38 of a motor 40. The motor is shown supported on a suitable bracket attached to the leg structure 12 at one end of the apparatus. It will be noted that the impeller 28 is rotated in the proper direction for moving the cleaning fluid through the inlet 22 from the tank 10 and elevating it through the passageway formed in the housing 24 for discharge at the outlet nozzle 26.

At the inlet of the housing 24 the passageway formed therein is of cylindrical form, but at the outlet 26 it is substantially wider in horizontal

direction and much narrower in vertical direction, and the intermediate portion of the passage varies gradually so as to merge smoothly with the inlet and outlet sections, as seen in Fig. 2. Preferably, the cross sectional area of the oblong discharge nozzle 26 is no greater than the area of the inlet at 22, and it may be somewhat less to insure some increase in velocity of the liquid upon its discharge from the outlet 26. As seen in Fig. 1, the terminal portion of the passage at the outlet 26 is directed obliquely downward toward the surface of the liquid at 16 so that the stream discharged from the outlet 26 will drive into the body of liquid in the tank 10, serving to agitate it to produce turbulence throughout the liquid body which will assist in loosening and removing dirt, grease, and other foreign matter from the parts under treatment.

Fig. 1 illustrates such parts as including engine pistons and connecting rods, a crank shaft and some spark plugs, and as shown, these parts are contained within a basket 44 removably disposed in the tank 10 and provided with bail or handles 46 at opposite ends so that it can be readily lifted out of the tank or lowered into it for handling the articles as a group. For larger pieces or individual mechanisms, the basket 44 may be dispensed with and the parts to be cleaned may rest directly upon the grill or reticulated support 18. This support 18 may be upheld at a distance from the bottom wall 11 of the tank by any suitable means, but as shown, it rests upon the rim of a pan or tray 48 which, in turn, rests upon the bottom of the tank and which is upwardly open to receive dirt and sludge which tends to settle and accumulate below the support 18 as a result of the cleaning operation. As shown, the support includes positioning lugs 50 which engage the walls of the pan 48 to insure firm lodgment of the support thereon. At each side, the pan may be provided with a bail or a handle 52 secured to the side wall of the pan at 53, 53 and extending upwardly near the top of the tank so that periodically the cleaning liquid may be drawn off by way of a drain cock 54 and the sludge pan 48 may be lifted out for convenient disposal of its contents. At the same time the residue of liquid remaining below the level of the drain cock 54 may be drawn off through a pet cock 56 in the bottom wall 11 of the tank.

Fig. 3 shows the impeller 28 mounted on one end of its drive shaft 30 and shows the bearing sleeve 32 for the shaft as provided with a mounting flange 60 which is bolted against the outer end of a hollow cylindrical boss 62 formed on the wall of the housing 24. To prevent leakage of the cleaning fluid along the shaft 30, the sleeve 32 is formed with journal bearings 64 and 66 at opposite ends of the sleeve and between these bearing portions the bore of the sleeve is enlarged at 68 and a grease cup 70 is fitted into the sleeve in communication with this enlarged bore 68. Lubricant is thus furnished not only to the bearing surfaces at 64 and 66, but the entire space in the bore 68 is filled with lubricant, preferably a grease of the consistency employed in water pumps and for like purposes. The presence of this body of grease effectively prevents the escape of the thinner cleaning fluid employed in the apparatus and at the same time keeps the drive shaft 30 efficiently lubricated. It may be noted from Fig. 3 that the hub 72 of the impeller 28 is slightly larger in diameter than the extreme end of the 75

bearing sleeve 32 adjacent the hub 72, so that if the hub is maintained in fairly close contact with the end of the sleeve, the entrance of liquid at this point is prevented. As shown, the sleeve 5 is tapered at 74 to reduce its extreme end below the diameter of the hub 72.

Figure 4 illustrates an apparatus embodying this invention arranged for use as a dish washer. Preferably, it is mounted in a stationary position so that permanent plumbing connections can be arranged for it and, as shown, the cleaning or washing tank 80 is positioned against a wall or back panel 82 through which a supply faucet 84 for hot water extends over the tank. 10 When the tank has been filled to the desired level indicated at 86, with hot water from the faucet 84, a quantity of strong soap or other cleaning reagent will be dissolved in the water and the heater shown as a gas burner 88 under the tank 80 will be lighted to maintain the cleaning bath at a high temperature. The motor 90 is then started to drive the impeller 92 for maintaining a continuous circulation of the cleaning fluid through the tank and through the 15 passageway 94 in the housing 96 which connects the outlet 98 from the tank with the inlet 100 discharging into the tank at, or slightly above, the liquid level 86 therein. This discharge inlet 100 is horizontally elongated and vertically contracted like the inlet 26 shown in Fig. 2, and the remainder of the housing 96 and its 20 passageway, as well as the impeller 92 therein, may be identical in form and construction with the corresponding parts of the apparatus shown 25 in Figs. 1, 2, and 3. Preferably, a drain pipe 102 opens upwardly at the level 86 to serve as an 30 overflow and to maintain this level.

The basket 104 containing the dishes or other 35 articles to be washed is lowered into the tank 40 to the position shown in Fig. 4, and is therein subjected to the cleaning action of the recirculating fluid. In practice, this fluid is discharged obliquely downward at the inlet 100 into the body of fluid in the tank at a rate of about 45 400 gallons per minute, which produces turbulence throughout the body of fluid in the tank and violently agitates it. The velocity and force with which the liquid is thus moved through the 50 tank causes it to exert a thorough scouring action on the dishes so that they are readily cleaned. The basket 104 then is lifted out by its handles 106 and placed in a drain tub 108 which preferably is about of the same horizontal 55 cross section as the tank 80 but which may not be so deep. A constantly open drain outlet pipe 110 leads to a sewer connection. Above the drain tub 108 the panel 82 carries a hot and cold water mixing fixture 112 to which there is connected a flexible hose 114 with a spray head 116 for use in rinsing the dishes, preferably with water hot enough to evaporate readily and leave them satisfactorily dry.

Figure 5 illustrates another adaptation of my apparatus for handling fluid in connection with a treatment which is not primarily a cleaning process. It is common practice among athletes and athletic teams, particularly among football players, to soak the feet periodically in a special bath which has the property of hardening the skin and thickening it, particularly on the soles of the feet, producing a desired tough, callous-like formation. The ingredients employed in this bath are more or less suspended in the liquid, usually water, or are in the form of an emulsion, 60 and the active ingredients readily separate from 65

the liquid if it is allowed to stand; therefore, it is necessary to keep the bath agitated continuously during its use for treating the feet. For this purpose, my apparatus is admirably adapted.

An elongated tank 120 is made with side walls not over 16 inches in height so that the players sitting along the side of the tank can conveniently rest their feet in it. As shown, the upper margin of the tank wall is bent inwardly and downwardly, as seen at 122, to avoid exposing any sharp edges. The treating fluid indicated at 124 is placed in the tank to the level shown at 126 and the fluid is continuously re-circulated through a passage formed in the housing 128 which connects an outlet 130 in the lower portion of the tank with an inlet 132 above or adjacent the liquid level 126. The construction of the housing 128 and its passageway is identical with that of the housing 24 shown in Fig. 1 and the housing 96 shown in Fig. 4. The motor 134 is connected by a belt 136 with an impeller 138 in the housing 128 adjacent the outlet 130, and the rapid rotation of this impeller serves to elevate the liquid through the passageway in the housing 128 and to discharge it forcibly into the tank and into the body of liquid 124 therein. The inlet 132 is horizontally elongated like the inlet 126 shown in Fig. 2, thus distributing the discharge across the width of the tank. The high velocity at which the liquid is fed through the inlet insures agitation of the entire body of liquid in the tank and keeps the active ingredients properly distributed or emulsified throughout the bath.

The motor 134 is shown mounted on a supporting plate 140 which extends inwardly over the end of the tank to which the housing 128 is connected and which serves as a guard to prevent anyone placing himself too near the discharge inlet 132. A curved guard plate or hood 142 extends over the motor 134 and includes a removable part 144 disposed adjacent the belt 136 and pulleys which it connects.

While there is shown and described herein certain structure embodying the invention, it is to be understood that the invention is not limited thereto or thereby and may assume various other forms and includes all modifications, variations, and equivalents coming within the scope of the following claims.

I claim:

1. A cleaning apparatus comprising a tank, a reticulated support for articles to be cleaned removably disposed in said tank, said tank being adapted to contain a supply of cleaning fluid extending from the bottom of the tank to a substantial distance above the said support, said tank having an outlet for the fluid in a vertical wall and below the normal fluid level and an inlet for said fluid in the same wall at a higher level than said outlet, a housing mounted exteriorly of the tank and providing a smoothly curved passageway connecting the inlet with the outlet, an impeller mounted for rotation in said passageway adjacent said outlet, and means for rotating said impeller in a direction and at a speed to draw fluid through said outlet, to elevate said fluid through the passageway, and to discharge it forcibly through said inlet into the tank, together with a drain tank mounted adjacent the first-mentioned tank and dimensioned to receive the reticulated support, a supply conduit for rinsing fluid adjacent the drain tank with a spray device connected thereto, a con-

stantly open outlet leading from said tank, and a heater disposed under the first-mentioned tank for maintaining the cleaning fluid therein at high temperature.

- 5 2. In apparatus of the class described, a unitary housing providing a passage having a single intake opening at one end and a single delivery opening at the other end, said openings being substantially in the same plane, the intake opening being of circular cross section, and a rotary impeller mounted in said opening, the diameter of the impeller being approximately equal to the diameter of said opening, the delivery opening being horizontally elongated and vertically narrowed as compared with the intake opening, and the intermediate portion of the passage being smoothly curved and substantially arcuate and being formed to merge smoothly with said intake and delivery portions.
- 10 15 3. In apparatus of the class described, a tank, a housing mounted on said tank and providing a passage having an intake opening of circular cross section at one end and a delivery opening at the other end, a rotary impeller mounted in said intake opening, said housing having an opening in its wall opposite said intake opening and co-axial therewith, a bearing sleeve extending through said last mentioned opening in fluid-tight relation to said wall, and a drive shaft for
- 20 25 30 35 40 45 50 55 60 65 70 75 the impeller journaled in said sleeve, the sleeve having bearing portions adjacent its end in which the shaft is rotatably fitted and having an enlarged bore intermediate said bearing portions, together with means for filling said bore with lubricant, a pulley on said drive shaft and a belt for driving said pulley, the delivery end of said housing being remote from said drive shaft and serving as a brace to resist pull exerted thereon by said belt.
4. In apparatus of the class described, a housing providing a passage having an intake opening of circular cross section at one end and a delivery opening at the other end, a rotary impeller mounted in said intake opening, said housing having an opening in its wall opposite said intake opening and co-axial therewith, a bearing sleeve extending through said last mentioned opening in fluid-tight relation to said wall, and a drive shaft for the impeller journaled in said sleeve, said impeller having a hub on the shaft fitting snugly against the end of said bearing sleeve, the end portion of said sleeve adjacent the impeller hub being at least as small as the hub so that its end surface is shielded by the hub from the force of liquid fed into the passage by the impeller, and driving means for said shaft exerting a lateral pull thereon, said housing extending in a direction opposite said pull and bracing said shaft against said pull.
5. In apparatus of the class described, a tank, a housing mounted on said tank and providing a passage having an intake opening of circular cross section at one end and a delivery opening at the other end, an impeller mounted in said intake opening, means for rotating the impeller at high speed in a direction to draw liquid through said intake opening, said means including a drive shaft on which the impeller is secured, said housing having an opening in its wall with an outwardly facing shoulder around the said opening, a bearing sleeve for the shaft extending through said opening and having a flange seated against said shoulder, and means on the outer end of the shaft providing a shoulder which is seated against the outer end of the

sleeve by the axial thrust of the impeller, thus urging said flange against the shoulder of the housing in liquid sealing relation thereto, driving means for said shaft exerting a lateral pull thereon, said housing being arcuate and extending in a direction away from said pull, and means for attaching the remote end of said housing to said tank and resisting said pull.

6. In apparatus of the class described, a housing providing a smoothly and continuously curved C-shaped passage having an intake opening at its lower end and a delivery opening at its upper end, said openings being located substantially in the same vertical plane, the intake opening being of circular cross section, the delivery opening being horizontally elongated and vertically narrowed as compared with said intake opening and the intermediate portion of the passage being formed to merge smoothly with said intake and delivery portions, and a rotary impeller mounted in the intake opening co-axially therewith, said impeller being of approximately the same diameter as said intake opening, together with means for rotating the impeller in a direction and at a speed to draw liquid through said intake opening, to elevate said liquid through the passage, and to discharge it forcibly from the delivery opening, the rotating means for said impeller exerting a pull on said housing tending to rotate said housing about its

intake opening, and a common support for said housing and last-named means.

JOSEPH D. RULE.
